UNITED STATES PATENT OFFICE

156,353

HANDKERCHIEF OR SIMILAR ARTICLE

Lucy Larssen, New York, N. Y.

Application January 23, 1948, Serial No. 143,993

Term of patent 14 years

(Cl. D3—12)

To all whom it may concern:

Be it known that I, Lucy Larssen, a citizen of the United States of America and a resident of New York city, county of New York, State of New York, have invented a new, original, and ornamental Design for a Handkerchief or Similar Article, of which the following is a specification, reference being had to the accompanying drawings, forming part thereof.

In the drawings:

Fig. 1 is a plan view of one corner of a handkerchief showing my new design, the remaining corners of the handkerchief being unornamented except for the edges thereof which are a continuation of those here disclosed; and

Fig. 2 is a section taken on the line 2—2 of Fig. 1.

I claim:

The ornamental design for a handkerchief or similar article, substantially as shown and described.

LUCY LARSEN.
